UNITED STATES PATENT OFFICE.

HARRY W. DYER, OF NEW YORK, N. Y.

DESIGN FOR A CHILD'S VEHICLE.

Application filed February 23, 1926. Serial No. 16,631. Term of patent 7 years.

To all whom it may concern:

Be it known that I, HARRY W. DYER, a citizen of the United States, residing at 514 West 122 Street, New York city, county, and State of New York, have invented a new, original, and ornamental Design for a Child's Vehicle, of which the following is a specification, reference being had to the accompanying drawing forming a part hereof.

The figure is an elevation of a child's vehicle, showing my new design.

I claim:

The ornamental design for a child's vehicle as shown.

HARRY W. DYER.
